The ornamental design for a monitor and printer stand, as shown and described.

DESCRIPTION

FIG. 1 is a perspective view showing our new design for a monitor and printer stand;

FIG. 2 is a front view of the stand of FIG. 1;

FIG. 3 is a side view of the stand of FIG. 1, the opposite side view being a mirror image thereof;

FIG. 4 is a top plan view of the stand of FIG. 1;

FIG. 5 is a bottom plan view of the stand of FIG. 1; and, FIG. 6 is a rear view of the stand of FIG. 1.

The dashed lines are for illustrative purposes only and form no part of the claimed design.

The broken line showing of features of the monitor and printer stand in FIGS. 2, 5 and 6 is included for the purpose of illustrating portions of the article and forms no part of the claimed design.
